UNITED STATES PATENT OFFICE.

HENRY B. KEIPER, OF LANCASTER, PENNSYLVANIA, ASSIGNOR TO THE STAR BALL RETAINER COMPANY, OF SAME PLACE AND JERSEY CITY, NEW JERSEY.

DESIGN FOR A BADGE FRAME OR HOLDER.

SPECIFICATION forming part of Design No. 32,984, dated July 24, 1900.

Application filed June 26, 1900. Serial No. 21,691. Term of patent 14 years.

To all whom it may concern:

Be it known that I, HENRY B. KEIPER, a citizen of the United States, residing in Lancaster, in the county of Lancaster and State of Pennsylvania, have invented and produced a certain new and original Design for a Badge Frame or Holder, of which the following is a specification, reference being had to the accompanying drawings, forming a part hereof.

This invention relates to frames or holders for campaign buttons or badges and the like; and it consists in the design therefor shown in the accompanying drawings, in which—

Figure 1 is a front view of a badge frame or holder which embodies the design. Fig. 2 is a rear view thereof, and Fig. 3 is an edge view thereof.

In general outline the frame or holder is circular, and it presents the appearance of a series of spherical bodies *a*, disposed in a circle and applied to the periphery of a disk or ring. As seen in edge view, as in Fig. 3, the edge of the disk or ring is double or concave, the spherical bodies *a* abutting against one

side *b* of the concave, such side being continuous, while they appear to be let into the other edge, so that, as shown in Fig. 1, the adjacent spherical bodies are separated by a quadrilateral or nearly-triangular figure *c*. The spherical bodies project slightly beyond the periphery of the disk or ring, as shown clearly in Fig. 2.

The characteristic feature of the design is the series of spherical bodies arranged in a circle and applied to the double or concave periphery of a disk or ring, the adjacent spherical bodies being separated when seen in front view by a portion of one side of the concave.

I claim as my invention—

The design for a badge frame or holder, substantially as shown and described.

This specification signed and witnessed this 20th day of June, A. D. 1900.

HENRY B. KEIPER.

In presence of—

JACK L. STRAUB,
JOHN H. MYERS.
